ANTON J. OBERG AND ROBERT R. STOEFFEN, OF LOS ANGELES, CALIFORNIA.

PLATE SUPPORT FOR COLOR-PROJECTION MACHINES.

Application filed August 18, 1928. Serial No. 300,500.

This invention relates to improved means for supporting the plates of color projecting machines and for propelling said plates, also to improved means for holding in place 5 between transparent plates an intermediate colored plate.

An object of the invention is to support the intermediate colored plate or plates in simpler or more efficient manner.

10 Another object of the invention is to provide improved means for mingling white light with colored light in such a manner as to produce novel and more attractive spotlight effects.

15 Still another object of the invention is to produce simpler and more dependable means for rotating the color projecting plate in combination with simplified means for supporting said plate and guiding it during its 20 rotary movement.

Other objects and advantages may herein-after appear.

Referring to the accompanying drawings which illustrate a preferred embodiment of 25 the invention,

Figure 1 is a front view of spotlight color wheel embodying the invention and illustrating also the means for rotating said wheel and for guiding its rotational movement.

30 Figure 2 is a partial cross section, the line of section being indicated by the line 2—2 of Figure 1.

Referring in detail to the drawings, our newly invented spotlight color wheel includes a central glass disk 5 having a plurality of colored sectors 6, the color of each sector being different from the colors of adjacent sectors. Along the margin of each sector is provided a plurality of preferably semi-circular transparent spots 7 being distributed in any suitable manner to cause white light to mingle with colored light when the disk is 40 rotated.

Against one side of the central colored disk 45 5 is fitted a transparent retaining disk 8 and against the other side thereof is fitted a cooperating transparent retaining disk 9. Around the three disks 5, 8, and 9 extends a supporting ring 10 having a keeper flange 11 50 on one side which abuts against the outer face of disk 8 and near its other side a groove 12 within which is seated a resilient, nearly complete ring 13 which retains the disk 9 in place. Each of the free ends of said ring is

provided with an inwardly bent finger-hold 55 14 to aid in manually removing and replacing the ring 13.

On ring 10 is provided a peripheral toothed portion 15 with which cooperates a toothed pinion 16 secured to the driving shaft 17. 60 Said driving shaft 17 is supported by a bearing 18.

The retaining ring 10 is provided at about its mid-width with an external peripheral groove 20 with which cooperates a guiding 65 wheel or disk 21 loosely mounted on the end portion of shaft 17 and held in place upon said shaft by a nut 22 secured to the outer end of said shaft. Within disk 21 is a bushing sleeve 23. A washer 24 is interposed between 70 nut 22 and the outer end of said sleeve, said washer aiding in retaining the rotatable wheel 21 in place.

At each side of the main rotary element is mounted an auxiliary guiding disk or wheel 75 25 which is supported on an auxiliary shaft 26 said guide wheels 25 also engage the groove 20 of ring 10.

In the embodiment of the invention illustrated in the drawings the colored disk 5 is 80 illustrated as being made up of a series of differently colored areas or segments 6 which are grouped around a central set of colored areas 6^a, the four last mentioned colored areas being each of a triangular shape and being 85 so arranged as to form a square.

It is to be understood that the invention is by no means limited to any particular grouping or arrangement of the areas of colored glass provided in order to produce the desired 90 color effect. Variously shaped fragments of glass plates may be placed between the outer plates 8 and 9 and securely retained in place by means of the annular flange 11 and the retaining ring 13 which cooperates therewith. 95

In the illustrated embodiment of the invention the pieces 6 and 6^a of differently colored glass which comprise the intermediate disk 5, are symmetrically shaped and are fitted to each other along their margins, being cut 100 away at their edges to form the uncolored spots 7.

Owing to the fact that the uncolored spots 7 are semi-circular in shape and are located in the edge portions of the glass plates which form the component parts of the colored glass disk 5, said uncolored spots may be readily provided for by grinding away an edge por- 105

tion of a plate wherever it is desired to form an uncolored spot, the grinding wheel used for this purpose being relatively narrow and having its periphery convexed from side to side to fit into the completed semi-circular cut-away portions.

The operation will be readily understood from the foregoing description. The toothed pinion 16 carried by the driving shaft 17 imparts rotary movement to the supporting ring 10 together with the glass elements carried thereby, said ring 10 being guided and kept in place during its rotational movement not only by the guiding disk 21 therebeneath, but 15 also by the auxiliary guide wheels 25.

We claim:

1. In a device of the class described a plate to transmit color effects, a retaining plate to engage each side of said plate, a supporting 20 ring encircling all of said plates and having a circumferential retaining flange on one side and an internal groove near the other side, a retaining ring to engage said groove to hold said plates in place within said supporting 25 ring, a drive shaft, a pinion mounted on said shaft and operatively engaging said ring to rotate the latter, said ring having an external circumferential groove, and a guide disk mounted on said shaft and engaging said 30 groove.

2. In a device of the class described, a composite disk to transmit color effects, the edge portions of component parts of said disk having concave cut-away portions to provide a plurality of distinct spots for the transmission of uncolored light, and means to rotate said disk. 35

3. In a device of the class described, a composite disk to transmit color effects, the edge portions of component parts of said disk having semi-circular cut-away portions to provide a plurality of distinct spots for the transmission of uncolored light, and means to rotate said disk. 40

4. In a device of the class described, a composite glass disk to transmit color effects, the component parts of said disk being of different colors and their edge portions being contiguous to each other and being provided with concave cut-away portions to transmit uncolored light, and means to rotate said disk to mingle uncolored light with colored light, the spots of uncolored light thus provided being straight on one side and curved on the opposite side. 45

In testimony whereof we affix our signatures.

ANTON J. OBERG.
ROBERT R. STOEFEN.
